VIBRATOR

William F. Purves and Sydney P. Harris, Stamford, Conn., assignors to Schick Incorporated, a corporation of Delaware

Application October 11, 1940, Serial No. 360,736

2 Claims. (Cl. 128—36)

This invention relates to hand-vibrators, by which is meant vibration-producing devices adapted to be mounted on some part of the hand to vibrate the fingers thereof, which in turn are applied to the portion of the anatomy to be treated.

One of the objects of the invention is to provide an improved, self-contained, electric hand-vibrator incorporating a vibratory electric motor, either of the unbalanced rotary armature type or the oscillating armature-type, which is compact and capable of being manufactured at low cost and in which operator fatigue, as the result of excessive vibration of the hand and forearm, is reduced to a minimum without impairing the efficacy of the device.

Another object of the invention is to provide a hand-vibrator adapted to be mounted on the backs of the fingers only of the operator and capable of utilizing a rotary electric motor of the impulse type as the power unit.

Another object of the invention is to provide for the adjustment of the intensity of the vibration imparted to the hand of the operator and hence to the patient.

A preferred form of the vibrator in which these and other objects of advantages are achieved is illustrated in the accompanying drawing: Fig. 1 showing the vibrator attached to the hand of an operator; Fig. 2 a cross-section on the line II—II of Fig. 1; Fig. 3 a cross-section on the line III—III of Fig. 2; Fig. 4 a similar section but with the motor in a different position of adjustment; and Fig. 5 the unbalanced armature of the motor.

The illustrated vibrator comprises a housing, consisting of a cover portion 1 and a base portion 2, the latter being of rectangular shape and dimensioned to seat on the backs of the fingers only of an operator so as to occupy the area bounded by the first (basal) and second joints of the fingers, and to seat on at least three of the fingers. A cushion pad 3, which may be shaped on its underside to conform roughly to the contour of the upper surfaces of the fingers, is shown riveted to the base.

Mounted within the housing, in such manner as to transmit its vibrations thereto, is a self-contained electric vibrator unit including an element normally acting to vibrate the device as a whole in a plane at right angles to the axes of the fingers. Preferably, and as shown, the unit comprises a small rotary motor and the vibration-inducing element a weight carried by the motor shaft.

The construction of the motor per se forms

no part of the present invention but it has been found that a simple, impulse motor of the small size and simple form currently employed in electric shavers, properly located and modified to the extent of adding an unbalanced weight to the armature shaft, has ample power to actuate a vibrator of the type herein disclosed. This results from the fact that, as distinguished from vibrators heretofore proposed to be driven by rotary motors, the device is mounted on and attached to the fingers only, rather than partly on the fingers and partly on the back of the hand, so that the entire output of the motor can be efficiently directed to effecting vibration of the fingers (as is desired) and not wasted in vibrating also the hand proper and the lower arm of the operator. By so confining the vibratory action to the fingers themselves, operator fatigue of the hand and arm is also minimized.

The illustrated motor will be recognized as including a field magnet 4, mounted in the housing with its axis of symmetry cross-wise of the fingers, a field winding 5, an armature 6 and contact make-and-break system generally designated 7 adapted for actuation by a cam 8 on the armature shaft. The unbalanced weight which serves to vibrate the device when the motor is in operation is conveniently applied to the armature itself in the form of a piece of lead 9 shaped to round out one of the hollows of the hour-glass shaped armature and secured in place as by a pin 10 passing through it and through a cover plate 11 riveted to the armature laminations.

As usually constructed such motors are not self-starting and as applied, for example, to electric shavers, are required to be provided with starting means, such as a wheel affixed to the armature shaft and made accessible by an opening in the housing; but it has been found that when provided with an unbalanced weight, such as above described, no such starting means is required and in consequence the motor can be fully enclosed. The inertia of the weighted armature is such that the motor is readily started by twisting the vibrator as a whole in the plane of rotation of the armature, somewhat as a watch or clock is started, the contacts of the make-and-break mechanism being thereby brought to closed position and the motor started, as will be understood.

Since hand vibrators are ordinarily used in connection with the massaging of different individuals and of varyingly sensitive parts of the body, it is desirable, although not essential, to

provide for the adjustment of the intensity of the vibration imparted to the fingers of the operator; and this is done according to the present invention by mounting the vibrator unit in such manner that it can be adjusted to shift the plane of vibration relative to the fingers and, preferably, so that the motor unit can be bodily rotated from a position in which its plane of vibration is at right angles to the fingers (the maximum intensity of vibration then being imparted to them) to a position in which its plane of vibration is at a lesser angle or even parallel to the plane of the fingers. In the latter position the fingers are subjected to a less violent motion in a vertical direction, a more or less lateral motion being imparted to them depending on the extent to which the unit is rotated.

According to the illustrated method of providing for such adjustment, the motor is mounted on a base plate 12 having flanges 13 upstanding at its ends in which are mounted studs 14, 15, suitably journaled in the end wall portions 16, 17 of the base of the vibrator. A hand wheel 18 pinned to stud 14 provides a convenient means for bodily rotating the motor and it may be locked in any desired position of adjustment by lock nut 19 threaded on stud 15. As so mounted the motor may be adjusted from the position shown in Fig. 3, in which the maximum vibration is imparted to the fingers (the plane of vibration then being vertical) to the position shown in Fig. 4 (or to any intermediate position, such as the one indicated in dotted lines) in which a more or less lateral motion is imparted to the vibrator and a lesser degree of vibration experienced by the patient.

It will be observed that the axis of rotation of the armature is located closer to one end of the base than to the other, the purpose of so locating it being to effect a somewhat greater intensity of vibration at one end of the base than at the other, although, as will be understood, the whole base does vibrate bodily. In the result, when the vibrator is applied to the fingers in the manner indicated, that is, with that end of the base which is closest to the armature located above the first finger and the end more remote from the armature located above the third finger, the first finger is actually vibrated to a greater ex-

tent than the second, and the second to a greater extent than the third. However, due to the fact that in most instances the developed strength and facility of manipulation of the fingers decreases from the first toward the little finger, the "feel" of the vibrator to the hand of the operator is of substantially balanced vibratory motion; and fatigue of the operator's fingers is reduced to a minimum.

10 The type of hand-attachment means illustrated in the drawing (which is the subject of a separate application and is of a construction in no way essential to the present invention) comprises a pair of wedge-shaped, molded buttons 20, which may be of molded rubber or any of the available rubber substitutes, attached to the vibrator base by elastic strap 21, the points of the wedges entering between the fingers, and the bases or enlarged heads of the buttons snugly engaging the lower sides and under surfaces of the fingers to hold the vibrator in firm contact with the backs of the fingers—without cramping the fingers and leaving them quite free to be manipulated during the massaging operation.

20 As will be understood from the scope of the appended claims, various features of the invention are of practical value and utility in vibrators of other forms of construction than the one illustrated.

30 The following is claimed:

1. A self-contained, electric hand-vibrator comprising a base for attachment to the back of the hand, a vibratory electric motor, means for supporting the motor in various positions of angular adjustment of the plane of vibration of the motor relatively to the plane of the base, and means for locking the motor in any selected position of adjustment.

2. A self-contained, electric hand-vibrator comprising a base for attachment to the back of the hand, an unbalanced rotary electric motor, means for supporting the motor on the base with freedom for bodily adjustment about an axis lying in the plane of vibration and intersecting the axis of rotation of the motor, and means for securing the motor in any selected position of adjustment.
